(57) **CLAIM**

The ornamental design for a launch monitor, as shown and described.

DESCRIPTION

FIG. 1 is a top front right side isometric view of a first embodiment of a launch monitor, showing the design.

FIG. 2 is a bottom rear left side isometric view of the launch monitor of FIG. 1.

FIG. 3 is a front view of the launch monitor of FIG. 1.

FIG. 4 is a rear view of the launch monitor of FIG. 1.

FIG. 5 is a left side view of the launch monitor of FIG. 1.

FIG. 6 is a right side view of the launch monitor of FIG. 1.

FIG. 7 is a top plan view of the launch monitor of FIG. 1.

FIG. 8 is a bottom plan view of the launch monitor of FIG. 1.

FIG. 9 is a top front right side isometric view of a second embodiment of a launch monitor, showing the design.

FIG. 10 is a bottom rear left side isometric view of the launch monitor of FIG. 9.

FIG. 11 is a front view of the launch monitor of FIG. 9.

FIG. 12 is a rear view of the launch monitor of FIG. 9.

FIG. 13 is a left side view of the launch monitor of FIG. 9.

FIG. 14 is a right side view of the launch monitor of FIG. 9.

FIG. 15 is a top plan view of the launch monitor of FIG. 9; and,

FIG. 16 is a bottom plan view of the launch monitor of FIG. 9.
